UNITED STATES PATENT OFFICE

ALBERT L. KLEES, OF LONG BEACH, NEW YORK, ASSIGNOR TO SURFACE COMBUSTION CORPORATION, OF TOLEDO, OHIO, A CORPORATION OF NEW YORK

GAS BURNING APPARATUS

Application filed July 10, 1929, Serial 377,100. Renewed November 13, 1931.

This invention relates to gas burning apparatus for house heating furnaces originally designed for burning solid fuel; and has for its object to provide a gas burning apparatus of such form and construction that a major portion thereof may be built as a unit for positioning in front of the ash pit chamber to form in effect a lateral extension thereof from the side door opening therein, the other portion being so constructed as to permit its being positioned within the furnace; and withal to provide a gas burning apparatus which shall be efficient in operation, simple in construction and otherwise particularly well adapted for its intended purpose.

The present application is a continuation in part of my application, Serial No. 202,833, filed July 1, 1927.

Referring to the drawings wherein the preferred form of the invention is shown:—

Fig. 1 is a perspective view showing the lower half of a house heating furnace and that portion of the gas burning apparatus which is outside of the furnace;

Fig. 2 is a plan view of the gas burning apparatus removed from the furnace, parts of the apparatus being omitted;

Fig. 3 shows how the burner end of the apparatus is arranged within the furnace, parts being in section;

Fig. 4 is a plan and sectional view of the outer end of the apparatus showing how gas and primary air are supplied to the burner mixing tubes;

Fig. 5 is an end elevation of the outer end of the apparatus stripped of its attachments;

Fig. 6 shows the interior construction of snap acting mechanism which may be employed for opening and closing the main gas valve, and

Fig. 7 shows in greater detail the constructional features of the baffle elements shown in Fig. 3.

The ordinary house heating furnace is provided with grates for burning solid fuel. To install my improved gas burning apparatus it is necessary to remove the grates and also the door for the ash pit chamber.

In accordance with the present invention, there is provided a casing 10 for supplying

secondary air to the burner 26 which replaces the furnace grates. The casing extends from the door opening in the ash pit chamber 12 whereby to form in effect a lateral extension of said chamber. The admission of air into the casing is controlled by a damper 34 shown as positioned in the top wall of the casing, means being provided for opening and closing the damper at the same time that the main gas valve 20 for the burner is opened and closed.

In the present instance, the gas valve actuating mechanism is shown as comprising a manually actuatable lever 36 projecting from one side of a housing 35 wherein is contained a mechanism for causing the valve to open and close with a snap action. The lever 36 and damper 34 are so interconnected, by mechanism generally indicated at 46, that when the lever 36 is moved to actuate the gas valve 20 it will also actuate the damper, the gas valve and damper being concurrently opened and closed as already stated.

For illustrative purposes, the said mechanism 46 is shown as comprising two link-connected bell cranks 11 and 15, the latter being connected to the damper 34 and the former to the lever 36 by a link 19. The bell crank 11 is shown as supported on a bracket 13 extending from the housing 35.

The snap action mechanism comprises a head 44 secured to the stem of the gas valve and laterally extending links 40 fulcrumed as at 43 to the head 40, the outer ends of the links being connected by a retractile spring 38 and being free to move between vertically spaced abutments 42 at each side of the housing 35. A link 37 connects the center of the spring 38 with the manual controlling lever 36. It will be, of course, understood that when the middle of the spring is moved past the fulcrum points 43, the outer end of the links 40 will move upwardly or downwardly as the case may be, thereby actuating the valve stem, to close or open the valve. Snap action mechanism of the type shown is well known in the art. In the present instance there is also shown associated with the head 44 a lever 48, the function of which is to prevent the gas valve from being opened

unless a thermostatic device 50, controlled by the burner pilot 47 permits.

The gas burner is of the multi-jet ring-type shown as comprising two similar sections 26 individually supplied with combustible mixture from individual mixing tubes 24 within the casing 10, the tubes delivering into individual pipes 52, which in turn deliver to the individual burner sections, the pipes having upturned extensions 54 to which the burner sections are detachably connected. The pipes may be supported adjacent their upturned extensions by hangers 53. The burner sections are supported in any suitable manner as by lateral arms 62 projecting from a common hub removably supported on a central standard 60.

Surrounding the burner in spaced relation to provide an annular passage 55 is a casing 56 and spaced from the inner rim of the burner to provide an annular passage 57 is a plate 58. The casing 56 is in effect a detachable extension of the casing 10, the casing 56 being split as indicated at 56'. The plate 58 is detachably supported on the standard 60. The purpose of the passages 55 and 57 is to confine and direct the secondary air, supplied by the casing 10, to flow paths immediately adjacent the burner whereby to insure proper combustion of the fuel.

In order that the hot gases from the burner may be deflected against the walls of the fire pot 68, there is provided a baffle 66 made up of a number of wedge-shaped members 66', the lower ends of which rest on a support 64 supported on the standard 60 and the upper ends of which lean against the fire pot wall. A cut-out 70 in the top of each baffle member insures free escape of the spent heating gases. In order to permit a given number of baffle members to be adjusted to fire pots of different diameters, and at the same time to prevent open gaps between the members, the latter are constructed to overlap as shown in Fig. 7.

At the outer end of the casing 10 is a closure 14 provided with openings 22 for admitting air to the respective mixing tubes 24, the walls of the openings being extended to form tubular bosses 23 whereinto the tubes project. Associated with each tube is a jet orifice gas nozzle 27 controlled by a needle valve 32 which is mounted in a body 28 which also forms a support for a shutter 30 for controlling the admission of air to the mixing tubes.

The nozzles 27 are mounted in the ends 26 of conduits 16 formed in the closure 14, the conduits having a common inlet whereinto the gas supply pipe 18 discharges. As clearly shown in Fig. 5, the walls of the conduits 16 are extended into the openings 22, the end of each conduit terminating in a tubular portion, in one end of which the nozzle 27 is

mounted and in the other end of which the body 28 is mounted.

The manufacturing and installation advantages of the apparatus as a whole will be readily appreciated by those skilled in the art, it being noted that the casing 10 and the parts housed and supported thereby constitutes a unit which forms in effect a lateral extension of the ash pit chamber.

What is claimed is:

1. In gas burning apparatus for furnaces having a fire pot and a chamber therebelow provided with a side opening, the combination of a gas burner for firing into said pot, a casing for supplying secondary air to the burner and being of a length to form a lateral extension of said chamber from said opening, means for controlling the admission of air into said casing, and means housed by and extending through the front wall of said casing for supplying a mixture of air and gas to said burner.

2. In gas burning apparatus for furnaces having a fire pot and a chamber therebelow provided with a side opening, the combination of a sectional gas burner for firing into said pot, a casing for supplying secondary air to said burner and being of a length to form a lateral extension of said chamber from said opening, means for controlling the admission of air into said casing, and means housed by and extending through the front wall of said casing for supplying a mixture of air and gas to said burner.

3. In gas burning apparatus for furnaces having a fire pot and a chamber therebelow provided with a side opening, the combination of a ring-type burner for firing into said pot, a casing for supplying secondary air to the burner and being of a length to form a lateral extension of said chamber from said opening, means individual to and spaced from the inner and outer rims of said burner to provide inner and outer passages for the flow of air from said casing, and means housed by said casing for supplying a mixture of air and gas to the burner.

4. In gas burning apparatus for furnaces having a fire pot and a chamber therebelow provided with a side opening, the combination of a gas burner for firing into said pot, a casing for supplying secondary air to said burner and being of a length to form a lateral extension of said chamber from said opening, a mixing tube for gas and air for the burner, said tube being housed by said casing, a closure for the outer end of the casing, said tube opening to the atmosphere through said closure, means including a gas cut-off valve for delivering gas to said tube, a damper for controlling the admission of air into said casing, and means for simultaneously actuating said valve and damper.

5. The combination with a gas burner, of

an elongated casing for supplying secondary air to the burner, a closure at the outer end of the casing and having an inlet for primary air, a mixing tube extending from said inlet and coupled to said burner, a gas nozzle positioned in said inlet for supplying gas to the burner, and means for controlling the admission of air into said casing.

6. The combination with a gas burner, of an elongated casing for supplying secondary air to the burner, a closure at the outer end of the casing and having an inlet for primary air, a mixing tube extending from said inlet and coupled to said burner, a gas nozzle positioned in said inlet for supplying gas to the burner, means for controlling the admission of air into the casing, a gas valve for controlling the admission of gas to said nozzle, and means for simultaneously operating said valve and said means.

7. In a furnace fire box provided with a burner for projecting a ring of flame thereinto and a baffle in said fire box for directing the flame from said burner against the sides of the fire box to be heated, the combination of a support for the burner and baffle comprising, a standard, laterally extending burner supporting means on the standard below the top thereof, and a baffle supporting plate mounted on the standard above said means.

8. In a furnace fire box provided with a burner for projecting a ring of flame thereinto and a baffle supported in said fire box for directing the flame from said burner against the sides of the fire box to be heated, the combination of a burner and baffle support comprising, a standard, a baffle supporting plate removably mounted on the standard, laterally extending burner supporting means removably mounted on the standard below said plate, and an air deflecting plate removably mounted on the standard above said burner supporting means.

45 9. In a gas burning appliance, the combination of an upright standard, a horizontally disposed air conduit terminating adjacent said standard, a riser gas pipe between said standard and the adjacent terminal of said conduit, an elongated horizontally disposed gas burner coupled to said pipe and partly supported thereby, and means on said standard providing additional support for the burner.

55 10. The combination with a furnace having a firebox and a chamber therebelow, of an upright tubular casing within said chamber and having an inlet for air, a laterally extending member positioned within said casing in a manner to form a ring-like space between its rim and the side walls of said casing, a gas burner positioned in said space in laterally spaced relation with respect to said member and the side walls of the casing whereby to form inner and outer ring-like

passages through which air entering the casing may find exit and thus supply secondary air to the burner, and means for supplying a mixture of air and gas to said burner.

11. The combination with a furnace having a firebox and an ash chamber therebelow, of an upright tubular casing within said chamber having a side inlet for air, a member partially closing the upper end of said casing in a manner to form a space between its rim and the side walls of said casing, a gas burner positioned in said space in laterally spaced relation with respect to said member and the side walls of the casing whereby to form inner and outer passages through which air entering the casing may find exit and thus supply secondary air to the burner, and means forming with the firebox an upwardly converging chamber above the burner.

12. The combination with a furnace having a firebox and a chamber therebelow, of an upright tubular casing within said chamber and having an inlet for air, a laterally extending member positioned within said casing in a manner to form a ring-like space between its rim and the side walls of said casing, a gas burner positioned in said space in laterally spaced relation with respect to said member and the side walls of the casing whereby to form inner and outer ring-like passage through which air entering the casing may find exit and thus supply secondary air to the burner, a standard concentrically positioned with respect to said burner and said member, and forming a support for said burner and member, and means laterally of said standard for delivering a mixture of air and gas to the burner.

13. The combination with a furnace having a firebox and a chamber therebelow, of an upright tubular casing within said chamber and having an inlet for air, a laterally extending member positioned within said casing in a manner to form a ring-like space between its rim and the side walls of said casing, a gas burner positioned in said space in laterally spaced relation with respect to said member and the side walls of the casing whereby to form inner and outer ring-like passages through which air entering the casing may find exit and thus supply secondary air to the burner, an upright standard forming a support for said member, a flame deflecting baffle disposed obliquely over the burner, and a baffle-supporting means supported by said standard.

14. Apparatus having utility with a furnace provided with a fire pot and an ash chamber having an opening in its side comprising in combination an air conduit adapted to project into said opening, an upright tubular casing adapted to be positioned within said chamber, said conduit discharging into said casing, a gas burner concentrically disposed within said casing adjacent the top

thereof, means projecting into said casing from said conduit for supplying premixed air and gas to the burner, and means for directing the hot gases from the burner towards the walls of the fire pot.

5 In testimony whereof I affix my signature.
